UNITED STATES PATENT OFFICE.

SAMUEL WEINSCHENK, OF CHESTER PARK, NEW YORK.

GARMENT.

No. 925,146.

Specification of Letters Patent.

Patented June 15, 1909.

Application filed January 12, 1909. Serial No. 472,038.

To all whom it may concern:

Be it known that I, SAMUEL WEINSCHENK, a citizen of the United States of America, and a resident of Chester Park, county of 5 Queens, State of New York, have invented certain new and useful Improvements in Garments, of which the following is a specification, reference being had to the accompanying drawings, forming a part thereof.

10 My invention relates to improvements in garments, and particularly to body coverings of jacket or vest-like form, of which the so called "coat sweater" is an example. This kind of garment is commonly made in two 15 forms,—one with an open low neck and no collar and the other with a high collar and a closed neck or chest protector.

It is the object of the present invention to produce a garment which combines these two 20 forms, in that it may be converted from a collarless low neck garment into a high collar closed neck garment at will, and to this end I provide the garment with a disappearing collar which may be folded down within 25 the garment so as to be entirely concealed when the garment is worn as a collarless low neck garment, but which is adapted to be folded up and over into a collar form and is provided with projecting tabs by which portions 30 thereof may be crossed over at the front of the garment so as to securely fasten it in position, and with folding lapels which may likewise be opened out to close the neck portion of the garment and serve as a chest protector, the lapels being adapted to be fastened 35 to the collar portion when the same is in operative position, all in a manner to be fully described hereinafter.

In order that my invention may be fully 40 understood, I will now proceed to describe an embodiment thereof, having reference to the accompanying drawings illustrating the same, and will then point out the novel features in claims.

45 In the drawings: Figure 1 is a view of the garment being worn as a collarless low neck garment. Fig. 2 is a similar view of the same garment with the parts adjusted to form a high collar closed neck garment. Fig. 3 is 50 a view of the garment opened out with the adjustable collar folded down to put the garment in condition to be worn as is shown in Fig. 1. Fig. 4 is a detail view of the front portion of a collar when the same is being 55 worn in the condition shown in Fig. 2, except that the portion of the collar which is

normally turned back upon itself when being so worn is turned up to show the relationship of the connecting tabs. Figs. 5, 6, and 7 are cross sectional views of the top 60 portion of the back of the garment showing the adjustable collar in its various positions.

The garment illustrated has the usual body or waist portion 10 which opens down the front and is closed by means of buttons 65 and button-holes 11. The neck of the garment is cut low as is shown at 12 (see Fig. 1), the edge of the neck portion being provided with lapels 13. These lapels are preferably provided with button-holes by which 70 they may be secured in their normal position against the body of the garment by means of buttons 14.

An adjustable folding collar 15 is provided, the same being preferably secured to 75 the body portion of the garment upon the inside thereof at some little distance down from the edge of the neck portion. This point of connection may be conveniently along the line of the seam 16 by which the 80 usual binding or edging strip 17 is secured to the remaining portion of the garment. This collar 15 normally lies against the inside of the garment so that when the garment is worn in the manner shown in Fig. 1 85 it is entirely concealed. When it is desired to employ the collar around the neck the said collar 15 is turned upward so as to bring the major portion thereof beyond the upper edge of the neck portion of the garment, the change in position being readily 90 seen by comparison of Figs. 5 and 6 of the drawings,—the former showing the collar as lying flat against the inside of the garment as is shown in Fig. 3, while the latter view 95 shows the collar as folded up and extending beyond the upper edge of the neck portion. The outer extremity of the collar 15 is thereafter folded over, as is shown in Fig. 7, so as to form an upright turned-down collar, and the collar in this position is adjusted around the neck of the wearer, as is shown 100 in Fig. 2. The said collar 15 is provided with end tabs 18 and 19, the former being provided with several buttons 20, while the latter is provided with corresponding button-holes 21; a button 22 is also located upon or in proximity to the tab 19. When the collar 15 is adjusted around the neck, as is 105 shown in Fig. 2, the tab 19 is crossed over the face of the tab 18 and the buttons 20 caused to engage the button-holes 21 as is

100

105

110

shown in Fig. 4. The lapels 13-13 are then unbuttoned from engagement with their buttons 14 and folded across the chest of the wearer to close the neck part 12, the button-holes in the lapels being caused to engage the said button 22, all as will be well understood by reference to Fig. 2 of the drawings. It will be readily understood that the garment so adjusted thoroughly protects the neck and chest of the wearer while the neck and chest is left quite free when the garment is worn in the condition shown in Fig. 1.

While I have shown my invention as applied to a coat sweater, it will, of course, be apparent that I may apply the same to other forms of garments constituting body coverings.

What I claim is:

1. In a garment of the class described, the combination with a body portion having a collarless low neck and provided with lapels,

of a folding collar secured to the body portion of the garment at a point within the same, the said collar being adapted to be folded outward to form an exposed collar, and means for fastening the lapels together across the chest of the wearer and also for fastening the said lapels to the collar portion.

2. In a garment of the class described, the combination with a collarless low neck body portion, the same being provided with lapels, of a disappearing collar secured to the inside of the body portion, the said collar being adapted to be folded outward to form a high neck collar, means for securing the ends of the collar to each other, and means for securing the lapels to each other and to the collar when the collar is being used as such.

SAMUEL WEINSCHENK.
